E. CRAIG,
BOX TOP STAPLER,
APPLICATION FILED APR. 15, 1918.

1,325,780.

Patented Dec. 23, 1919.

Inventor
Edward Craig
By Arthur F. Durand
Atty.

UNITED STATES PATENT OFFICE.

EDWARD CRAIG, OF ST. JOSEPH, MICHIGAN.

BOX-TOP STAPLER.

1,325,780.

Specification of Letters Patent.

Patented Dec. 23, 1919.

Application filed April 15, 1918. Serial No. 228,555.

To all whom it may concern:

Be it known that I, EDWARD CRAIG, a citizen of the United States of America, and resident of St. Joseph, county of Berrien, and State of Michigan, have invented a certain new and useful Improvement in Box-Top Staplers, of which the following is a specification.

This invention relates to stapling machines for stapling together the flaps or thicknesses of the top of a box of that kind in which the upper end of the box has a restricted mouth or opening through which an element of the stapling machine, such as the anvil or clench-block thereof, must be inserted in order to perform the stapling operation by which the various thicknesses or flaps of the top are secured together.

Generally stated, the object of the invention is to provide a novel and improved stapling machine of the foregoing general character.

It is also an object to provide an improved construction and arrangement whereby the anvil or clench-block of the stapling machine may be moved into position to facilitate the adjustment of the box thereon, or preliminary to the stapling operation, and whereby the box will be firmly and rigidly supported during such operation.

It is also an object to provide certain details and combinations tending to increase the general efficiency and desirability of a box-top-stapler of this particular construction.

To these and other useful ends, the invention consists in matters hereinafter set forth and claimed.

In the accompanying drawings:—

Figure 1 is a side elevation of a box-top-stapler embodying the principles of the invention, showing a box in position to be stapled.

Fig. 2 is a horizontal section on line 2—2 in Fig. 1.

Fig. 3 is a side elevation of a clench-block or anvil and the supporting arm therefor, showing a different form of the invention.

As thus illustrated, the invention comprises a body having a base 1, an upright portion 2, and a forwardly extending arm 3 at the top thereof. Said arm 3 has its front end provided with a stapling mechanism 4 of any suitable, known or approved character, operated by a pulley 5 through the medium of a shaft 6 connected thereto.

The driving power is controlled by a clutch 7, of any suitable known or approved character, and this clutch is controlled by a foot-lever 8 through the medium of a rod 9, a bell-crank 10, and another rod 11, whereby the operation of the stapling mechanism can be started and stopped at will.

To support the box in position to receive the staples, the arm 3 is preferably provided with a depending boss 12, said boss being bored vertically to receive the upright stem portion 13 of the supporting arm 14 upon the outer end of which the anvil or clench-block 15 is mounted. In this way, the arm 14 is swiveled to turn about a horizontal axis, to facilitate the adjustment of the box thereon. The arm 14 can be swung outward in any suitable or desired manner, but as a matter of further and special improvement, the stem 13 is provided with a laterally extending arm 16 to which is connected a rod 17, which rod is in turn connected with a bell-crank 18 pivoted on the side of the body of the machine. A rod 19 connects the bell-crank 18 with another bell-crank 20 pivoted on the side of said body, and a rod 21 connects this bell-crank 20 with the foot-pedal 22 pivoted on the front end of the base of the body. With this arrangement, downward pressure on the foot-pedal 22 will exert a pull on the rod 17, and this will swing the arm 14 around into position approximately at right angles to the arm 3, so that the box can be easily adjusted thereon.

The box itself, of course, may be of any suitable character. For example, it may comprise side walls 23 and a top 24, said top being composed of two or more thicknesses and provided with a central opening 25 which forms the restricted mouth or opening for the top or upper end of the box. The arm 14 is of a length and shape to be inserted through the opening 25, and the thicknesses of the top of the box are then stapled together by staples inserted through these flaps or thicknesses and clenched upon the anvil or clench-block 15, the staples being located or driven wherever necessary or desirable. Any suitable means, such as a spring 26 applied to the rod 19, can be employed for returning the arm 14, and also the pedal 22 and its connections with said arm, to normal positions after the pedal is released. The upper end of the arm 13 can be provided with a removable nut 27, to detachably hold it in place, and the arm 13,

which is hollow, so that said nut 27 is inclosed, may have its upper side provided with a removable cover 28, affording access to said nut. The stem 13 may be provided 5 with a collar or shoulder 29 which bears against the underside or lower end of the boss 12, so that when the nut 27 is tightened the arm 14 will be drawn upward to a certain definite height, whereby the clenched-block 15 will be properly supported in position to receive the staples.

As shown in Fig. 3, the anvil 15 is mounted on the arm 30 which swings on the pivot 31, which latter is in the form of a 15 screw adapted to be inserted in the bottom of the boss 12, whereby the arm 30 and its anvil 15 will swing about a vertical axis. With this arrangement, the arm 30 can be removed by simply detaching the screw 31 20 from the boss 12, instead of by first removing the cover 28 and then unscrewing the nut 27, as is necessary with the construction shown in Fig. 1. It will be understood, of course, that the head portion 32 of the arm 30 is provided with a lateral arm, similar to the arm 16, so that the arm 30 can be controlled by the foot-pedal 22 through the medium of the rods and bell-cranks, in the manner previously described.

30 The swinging movements of the arm 14, or of the arm 30, about the vertical axis provided by the swivel can be limited in any suitable or desired manner. The collar or shoulder 29 may have a top lug 33 which 35 moves back and forth in the slot 34 formed in one side of the lower end of the boss 12, said slot being of a length to properly limit the swinging movements of the arm 14, whereby this arm will have its return movement under the influence of the spring 26 limited in such a manner that the clenched-block or anvil 15, when the foot-pedal 22 is released, will be accurately positioned below the stapler. For the same purpose, it 40 will be understood that the upper end of the head portion 32 of the arm 30 can be provided with a lug similar to the lug 33 to move back and forth in the slot 34, thereby to limit the swinging movements of the arm 30 in a manner that will be readily understood.

It will be understood, of course, that the box can be manipulated in any suitable manner to properly receive the staples. As 55 shown, and after the box is inserted in position, with a portion of the top 24 thereof resting on the anvil 15, the box can then be rotated about a vertical axis to bring different portions of the top into position to 60 properly receive the staples. For this purpose, of course, the means for supporting the anvil 15, such as the arms 14 and 30 shown and described, are adapted to enter the restricted mouth or top of the box, and 65 to then permit rotation of the box about a

vertical axis to successfully bring different portions of the top into position to receive the staples.

Furthermore, it will be seen that the rod 17 extends horizontally across the top of 70 the box, and the operator may manipulate the box in such a manner that the rear portion of the top 24 will always bear upwardly against this rod 17, thus insuring a level condition of the top of the box during 75 each stapling operation.

What I claim as my invention is:—

1. In a stapling machine, an upright support, a forwardly extending stationary arm at the upper end of said support, a stapler 80 mounted on the end of said arm, an anvil below said stapler, and means depending from said stationary arm to support said anvil, said means being adapted to enter the restricted mouth or opening in the top of a 85 box to bring said anvil below the superimposed thicknesses of which the top of the box is composed, so that one or more staples can be inserted in the top of the box.

2. A structure as specified in claim 1, said 90 means comprising an arm upon which said anvil is mounted and which is swiveled to swing about a vertical axis.

3. A structure as specified in claim 1, and means for moving said anvil into and out 95 of position below the stapler.

4. A structure as specified in claim 1, said 100 means comprising a support upon which said anvil is mounted and which is movable about a vertical axis, in combination with a foot-pedal suitably connected for controlling said support to move said anvil into and out of position below the stapler.

5. A structure as specified in claim 1, said 105 means comprising an arm swiveled to swing about a vertical axis, said anvil being mounted on the swinging end of this movable arm, means to limit the swinging movements of said movable arm, and a foot-pedal connected to control said movable arm.

6. In a stapling machine, the combination of a support, a stapler mounted on said support, an anvil below said stapler, and means depending from said support to carry said anvil, said means being adapted to enter 110 the restricted mouth or opening in the top of a box, so that one or more staples may be inserted in the material forming the top of the box, said means being adapted to permit rotation of the box about a vertical axis to 115 bring different portions of the top thereof into position to properly receive the staples.

7. A structure as specified in claim 6, and means including a horizontally disposed rod for swinging said anvil about a vertical axis, 120 said rod being adapted to engage the top of the box during the stapling operation.

Signed by me at St. Joseph, Michigan, this 14th day of March, 1918.

EDWARD CRAIG.
